DANDELION DIGGER OR SIMILAR ARTICLE

Richard L. Clifton, 2623 N. Cooper, Colorado Springs,
Colo. 80907

Filed Oct. 19, 1967, Ser. No. 9,068

Term of patent 14 years

(Cl. D35—2)

FIGURE 1 is a front elevational view of the dandelion digger or similar article of the present invention with a portion thereof broken away for convenience of illustration.

FIGURE 2 is a side elevational view of the said invention. The opposite side view is a mirror image of the side shown with a portion thereof broken away for convenience of illustration.

FIGURE 3 is a rear elevational view of the said invention with a portion thereof broken away for convenience of illustration.

FIGURE 4 is a bottom of the dandelion digger of the present invention.

FIGURE 5 is a top view of the said invention.

I claim:

The ornamental design for a dandelion digger or similar article, as shown and described.
